UNITED STATES PATENT OFFICE.

HARRY G. WEBSTER, OF CHICAGO, ILLINOIS, ASSIGNOR TO MILO G. KELLOGG, OF CHICAGO, ILLINOIS.

TELEPHONE-EXCHANGE SYSTEM.

No. 907,659.

Specification of Letters Patent.

Patented Dec. 22, 1908.

Application filed February 12, 1906. Serial No. 300,702.

To all whom it may concern:

Be it known that I, HARRY G. WEBSTER, a citizen of the United States, and resident of Chicago, county of Cook, and State of Illinois, have invented new and useful Improvements in Telephone - Exchange Systems, of which the following is a specification.

The present invention relates to telephone systems generally, and more particularly to the arrangement of circuits and apparatus by which the operator and subscriber may signal each other and by which the operator may be informed of the operative condition of a connected telephone line, and consists in a novel organization of circuits and apparatus associated with the line circuit which is utilized, together with the link-circuit and the subscriber's equipment, in performing these functions.

In carrying out my invention, I arrange the cut-off and line relays so that the resistances of their windings may be utilized in the control of the supervisory signal associated with the link-circuit. This is preferably accomplished by arranging these relays and their connections so that when the link-circuit is connected to the line by the insertion of the usual connecting plug into one of the line jacks, energizing windings of the line and cut-off relays are connected in bridge of the telephone line limbs and directly in circuit with the supervisory signal associated with the connected plug. The closing of this circuit alone causes the display of the supervisory signal; while the usual connection of the line limbs at the substation completes a path in shunt to the line and cut-off relay windings thus connected in bridge, thereby varying the current flow through the supervisory signal sufficiently to cause its effacement. In this organization, I preferably employ, for the control of the supervisory signal, a relay of the so-called "double acting" type, which I have disclosed in prior applications for Letters Patent. Such a relay may be varied in form, but preferably is so constructed that its contacts may be moved through a portion of their maximum range in response to a given energization, and through the remainder of the range in response to a greater energization—the former to light a signal lamp, and the latter to extinguish it. In developing this general organization, I have devised certain novel cir-

cuit arrangements which are not limited to the present system, but are capable of use in other relations.

The invention in its different aspects and its various subsidiary features will be more fully understood upon reference to the following detailed description, taken in connection with the accompanying drawing, and its scope will be particularly indicated in the appended claims.

In said drawing, Figure 1 is a diagram of a manually operated multiple telephone system, presenting one embodiment of my invention; and Figs. 2, 3 and 4 are diagrams of modified line circuit arrangements which may be used with the link-circuit arrangement of Fig. 1.

Referring in detail to said drawing and, for the present, to Fig. 1, A and B designate substations which are connected to the central office C by suitable telephone lines. The equipment at substation A, which may be of any preferred type, is here shown as embodying a call-bell 1 in series with a condenser 2, normally maintained in bridge of the telephone line limbs 3—4 by the engagement of the switch-hook 5 with the fixed contact 6. The transmitter 7 and the receiver 8 are connected, between the line limbs 3 and 4, in a normally open bridge which may be closed by the engagement of the switch-hook 5 with the fixed contact 9 whenever the receiver 8 is removed from the switch-hook 5. While the receiver remains in place, a path is provided through the call-bell 1 and condenser 2 for incoming ringing current, while its removal completes a path for battery current from a suitable central office source, through the transmitter and receiver. At the central office, the telephone line limbs 3 and 4 are extended to the contacts 10 and 11 of the usual spring jacks 12 and to the terminals of a suitable source of current 13. Line limb 3 is normally connected to ground at the contacts 14 and 15 of a cut-off relay 16, but may be conductively united to the jack contacts 11 by the movement of the contact 14 into engagement with the cut-off relay contact 17 upon the energization of said relay. The line limb 4 is connected to the live pole of the battery 13 by way of the conductors 18 and 19. The former conductor includes an energizing winding 20 of the line relay 21 and is normally united to the conductor 19 by the relay contacts 22 and 23. The con-

ductor 19 includes an energizing winding 24 of the line relay 21. The line signal, which is preferably an incandescent electric lamp 25, is included between the live pole of the battery 13 and ground by a normally open bridge including the conductors 26 and 27. This bridge is normally closed at the cut-off relay contacts 14 and 28, and is normally open at the line relay contacts 29 and 30. The energizing winding 31 of the cut-off relay 16 is permanently connected to the jack contacts 11 in an open circuit which may be closed at the line relay contacts 32 and 33 to bring the line relay winding 20 and the cut-off relay winding 31 into bridge of the telephone line limbs.

The circuits and apparatus, thus far described in connection with substation A, are duplicated at substation B and are designated by similar primed characters.

At the central office, connection is established between the desired telephone lines by means of the link-circuit comprising the strands 34 and 35, which unite the tip contacts 36 and 37 of the answering and calling plugs 38 and 39 respectively, and the strands 40 and 41 which unite sleeve contacts 42 and 43 of said plugs. These strands are provided with the usual condensers 44 and 45, which permit the passage of voice currents and, by refusing the passage of battery currents, maintain the signaling apparatus at the opposite ends of the link-circuit independent. At the answering end of the link-circuit, a "double acting" relay 46 is provided for the control of a supervisory signal lamp 47. The relay is provided with a winding 48, which is included between the live pole of the battery 49 and the sleeve strand 40 of the link-circuit, and a winding 50 which is included between the grounded pole of the battery 49 and the tip strand 34 of the link-circuit. The relay contacts 51, 52 and 53 are arranged so that upon a given pull of the magnet of the relay 46, the contacts 52 and 53 will be brought into engagement to complete the circuit from the live pole of the battery, through the supervisory lamp 47, to ground; and upon a further pull, will break this grounded connection by separating the contacts 51 and 52. A similar relay 46' is provided with windings 48' and 50', similarly connected between the battery and the sleeve and tip strands 41 and 35 of the calling plug 39, and is provided with similar contacts 51', 52' and 53' for controlling the lighting and extinguishment of the supervisory lamp 47'. The strands 35 and 41 are provided with the usual listening-key levers 54-55, which may be depressed to close a bridge including the operator's receiver 56, a condenser 57, and the secondary winding of an induction coil 58, the operator's transmitter 59 being included in a local circuit 65 with the primary winding of the induction

coil 58 and a battery 60. The strands 35 and 41 are also provided with the usual ringing key, whose levers 61 and 62 normally engage fixed contacts 63 and 64 to maintain the continuity of said strands. These levers may be depressed into engagement with the supplementary levers 65 and 66 to press the latter into engagement with the fixed contacts 67 and 68 to include ringing generator 69 in bridge of the strands 35 and 41. The engagement of the ringing key levers 61 and 62 with the supplementary levers 65 and 66 completes a second bridge including the battery 70 and impedances 71 and 72 located on opposite sides thereof, one pole of the battery being grounded at 73.

In the operation of the system, assuming that a party at substation A desires to converse with a party at substation B, he removes his receiver 8, thereby completing a circuit for current which will actuate the line relay 21 to cause the display of the line lamp 25. This circuit extends from the live pole of the battery 13, through conductor 19 including the line relay winding 24, cut-off relay contacts 23-22, conductor 18 including the line relay winding 20, line limbs 4 and 3 including the closed bridge at the substation through the receiver and transmitter, and cut-off relay contacts 14 and 15, to ground. This will cause a flow of current through the line relay windings 20 and 24 which will act in opposition in the two windings, but, by reason of the greater number of turns on the winding 24, will sufficiently energize the relay to attract its contacts 29 and 32—the former to close the local circuit of the line lamp 25, and the latter to complete the bridged connection of the winding 31 of the cut-off relay 16. Upon observing the display of the lamp 25, the operator will insert the answering plug 38 into one of the jacks associated with the line 3-4 and thereby complete a circuit from the live pole of the battery 49, through the winding 48 of the supervisory relay 46, sleeve strand 40, plug and jack contacts 42-11, energizing winding 31 of the cut-off relay 16, line relay contacts 32-33, line relay winding 20, conductor 18, jack and plug contacts 10 and 36, strand 34 and winding 46, to the grounded side of the battery 49. This circuit will sufficiently energize the cut-off relay 16 to break the call lamp circuit at the contacts 14-28 and to disconnect the battery 13 from the line at the contacts 22-23. It will be noted that, by reason of the arrangement of the windings of the line relay and their connections, the circuit just completed reverses the direction of current flow in the winding 20 and cuts the winding 24 out of circuit. This reversal in the winding of smaller turns produces a polarity in agreement with that previously produced by the flow of current through the winding 24 of a 100

larger number of turns, from the battery 13. The two windings 24 and 20 are so proportioned that the energization of the winding 20 from the battery 49 will retain the line relay in its actuated position. With the line and cut-off relay contacts in this position, the switch-hook 5 at the substation A will control a path in shunt to the bridged cut-off relay winding 31 and line relay winding 20. With this shunt path closed, the flow of current through the windings 48 and 50 of the supervisory relay 46 will energize said relay sufficiently to separate the relay contacts 51 and 52, thus preventing the lighting 15 of the lamp 47. If, however, the shunt path through the substation is opened, the flow of current through the bridged relay windings will be sufficiently less to allow the contacts 51 and 52 to come into engagement, without 20 allowing the contacts 52 and 53 to separate. Thus, it will be seen that the open or closed condition of the bridge at the substation will be indicated by the lighting or extinguishment of the supervisory lamp 47.

Upon establishing connection with the line 3-4, the operator will depress her listening-key levers 54-55 to close the bridge through her receiver 56; and after learning that the calling party desires connection with substation B, she will touch the tip contact 37 of the calling plug 39 against one of the jack contacts 11' to determine the idle or busy condition of the line 3'-4'. If this line is connected with another link-circuit, or if the subscriber at substation B has removed his receiver in the act of calling, the contact 11', touched by the tip 37, will have a potential above that of ground, due in the first instance to a flow of current from the live pole 40 of the battery 49 associated with the link-circuit, over its sleeve strand 40 or 41, to the connected jack contact; and in the second instance, to current from the battery 13' over conductor 19', cut-off relay contacts 23'-22', line relay contacts 33'-32' and cut-off relay winding 31' to the jack contact. Therefore, upon touching the tip contact 37 to the jack contact 11' of a busy line, a flow of current will result over the tip strand 35, to ground, 45 through the supervisory relay winding 50'. This will disturb the normal charge on the condenser 57 and cause a "click" in the operator's receiver 56. The normal charge of the condenser 57 is obtained from the battery 49 when the listening-key levers 54 and 55 are depressed.

If the operator finds that the line is idle, she will insert the calling plug 39 into the jack 12'. This will at first close a circuit 60 through the line relay 21', which will be immediately followed by the breaking of said circuit and the closing of a second circuit through the cut-off relay winding 31' and the line relay winding 20' in bridge of the line 65 limbs 3'-4'. The first circuit will extend

from the live pole of the battery 13', through the conductor 19' including the winding 24' of the line relay 21', cut-off relay contacts 22'-23', line relay winding 20', conductor 18', jack and plug contacts 10'-37, strand 70 35, winding 50' of the supervisory relay 46', to ground. This will energize the line relay 21' sufficiently to close its contacts 29'-30' and 32'-33', thereby connecting the winding 31' of the cut-off relay 16', and the winding 20' of the line relay, directly in circuit with the jack contacts 10'-11'. As soon as this takes place, the cut-off relay is energized by current from the battery 49, over the sleeve strand of the link-circuit, through the 80 bridged relay windings and back over the tip strand of the link-circuit to the grounded side of the battery 49. The energization of the cut-off relay interrupts the circuit first closed through both windings of the line relay, disconnects the battery 13' from the line and interrupts the circuit of the line lamp 25'. With the parts in this position, the operator sends ringing current over the line limbs 85 3'-4' to actuate the call-bell 1' at substation 90 B by depressing the ringing-key levers 61 and 62. At this time, in order that the line and cut-off relays may be held in their actuated positions, the battery 70 is provided, since the depression of the ringing-key levers 95 breaks the strands 35 and 41, thereby disconnecting the battery 49 from the line. The impedances 71 and 72 prevent the short circuiting of the generator 69. Prior to the answering of the call at substation B, and while 100 current is supplied to the line and cut-off relays from the battery 49, the supervisory relay 46' is sufficiently energized to complete the circuit of the supervisory lamp 47' and thereby cause its display. As soon, however, as the call at substation B is answered, the shunt path through the substation is closed, and the flow of current through the windings of the supervisory relay 46' is increased sufficiently to separate the contacts 110 51' and 52' and thereby break the circuit of the supervisory lamp 47' to cause its extinguishment. With the parties thus connected, the supervisory lamps 47-47' will remain dark during conversation; but as soon 115 as either party hangs up his receiver, the associated supervisory lamp will light, and the lighting of both lamps 47-47' will be an indication to the operator to disconnect.

From the previous description, it will be 120 seen that the cut-off relay depends for its operation upon the establishment of certain conditions, these conditions being the engagement of the line relay contacts 32-33 and the plug and jack contacts 42 and 11. 125 The engagement of the former contacts is under the several control of the subscriber and operator, being operated in the former case when the subscriber removes his receiver from its hook; and in the latter case 130

by the engagement of the plug and jack contacts 36 and 10. The other condition necessary to the operation of the cut-off relay—namely, the engagement of the plug and jack contacts 42 and 11—is under the sole control of the operator.

In the modified line circuit arrangement illustrated in Fig. 2, the line limbs 3 and 4 are extended, as before, to the jack contacts 10 and 11, and the substation equipment is identical. The line limb 3 is also normally connected to ground through similar contacts 14^a—15^a of the cut-off relay 16^a. In this case, the line relay 21^a has its winding included in circuit between the line limb 4 and the live pole of the battery 13^a, through the cut-off relay contacts 74—75 and a resistance 76. The line lamp 25^a is included, as before, between the live pole of the battery 13^a and ground, by a normally broken bridge including the conductors 26^a and 27^a. This bridge is normally open at the cut-off relay contacts 29^a—30^a and normally closed at the cut-off relay contacts 14^a—28^a. The winding of the cut-off relay 16^a is normally connected between the jack contact 11 and ground, by way of the cut-off relay contacts 77—78. In the operation of this system, the closing of the bridge at the substation completes a circuit from the live pole of the battery 13^a, through resistance 76, cut-off relay contacts 75—74, line limbs 4—3, cut-off relay contacts 14^a—15^a, to ground. The line relay is thereby energized and completes the normally broken circuit of the line lamp 25^a at the contacts 29^a—30^a, causing the display of the line signal. Upon the insertion of a plug into a jack of the line, either for the purpose of answering or making a call, current will be supplied from the live pole of the battery 49, over the sleeve side of the link-circuit, through the winding of the cut-off relay 16^a, cut-off relay contacts 77—78, to ground. The closing of this circuit energizes the cut-off relay 16^a sufficiently to separate its contacts 74 and 75, 77 and 78, 14^a and 15^a and 14^a and 28^a. The separation of the contacts 77 and 78 is brought about by the engagement of the armature contact 74 with the movable contact 78; and as long as the relay remains energized, these contacts 74 and 78 remain in conductive engagement, thus bringing the windings of the line and cut-off relays in bridge of the telephone line limbs. The actuation of the cut-off relay similarly disconnects battery 13^a, interrupts the circuit of the line lamp 25^a, and completes the connection of the line limb 3 to the jack contact 11.

In the line circuit arrangement illustrated in Fig. 3, the line limbs are continued, as before, to the jack contacts 10 and 11, and the line limb 3 is normally connected to ground by the contacts 14^b and 15^b of the cut-off relay 16^b. The line relay 21^b has its wind-

ing connected in circuit between the line limb 4 and the live pole of the battery 13^b by way of the cut-off relay contacts 79—80. This path also includes the line signal lamp 25^b. The circuit of the line signal lamp 25^b is continued from the live pole of the battery 13^b to ground by way of the normally closed cut-off relay contacts 79—80—81 and the normally open line relay contacts 29^b—30^b. A resistance 82 is included between the line relay contact 30^b and ground. When the cut-off relay 16^b is energized, the contact 14^b engages the contact 17^b to short circuit the lower half 83 of the winding of the cut-off relay, and the contact 79 engages the fixed contact 84 to include the upper half 85 of the cut-off relay winding and the winding of the line relay 21^b in bridge of the telephone line limbs. In this system, upon closing the bridge at the substation between the line limbs 3 and 4, current is supplied from the battery 13^b, through the lamp 25^b, cut-off relay contacts 80—79, line relay winding, line limbs 4 and 3, cut-off relay contacts 14^b and 15^b, to ground. The closing of this circuit energizes the line relay 21^b sufficiently to complete the circuit of the line lamp 25^b through the line relay contacts 29^b—30^b and resistance 82 to cause said lamp to light, as a signal to the operator that connection is desired. Upon the operator inserting a plug into a jack, either in answering or making a call, current will be supplied from the battery 49, over the sleeve side of the link-circuit, through the lower half 83 of the cut-off relay winding, to ground by way of the cut-off relay contacts 14^b—15^b, thus energizing the cut-off relay to attract its movable contacts 14^b and 79. As indicated diagrammatically by the spring on the contact 14^b, this contact is arranged to leave the contact 15^b only after the contact 79 has engaged the contact 84. The engagement of the contacts 79 and 84 completes a bridge between the telephone line limbs, through the upper half 85 of the winding of the cut-off relay and the winding of the line relay. The completion of this second circuit, prior to the short circuiting of the lower half 83 of the winding of the cut-off relay, retains the contacts 14^b and 79 in their attracted positions. The attraction of the contact 79 breaks the circuit of the lamp 25^b and, by short circuiting the lower half 83 of the winding of the cut-off relay, removes its impedance from the line limb 3 and thereby from the talking circuit.

In the line circuit arrangement illustrated in Fig. 4, the line limbs 3 and 4 are continued, as before, to the jack contacts 10 and 11, but the line limb 3 is not normally connected directly to ground as in the previous cases, but is connected by way of the cut-off relay contacts 14^c—15^c and conductor 86, including a winding 87 of the line relay, to the live pole 13^c.

of the battery 13°. The call signal lamp 25° is included in circuit between the live pole of the battery 13° and ground, by way of the line relay contacts 29° and 30°—in this case, 5 a single break only being provided in its circuit. In this instance, the cut-off relay 16° has its winding included in circuit between the jack contacts 11 and one strand of a “twin” winding 88 on the core of the line relay 21°. The center of the “twin” winding is connected to ground by way of the cut-off relay contacts 89 and 90, and the other strand is connected to the line limb 4. The cut-off relay contact 14°, when in its alternate position, 10 engages the fixed contact 17° to connect the line limb 3 directly to the contacts 11 of associated jacks. In the operation of this system, the closing of the bridge at the substation completes a circuit from the live 15 pole of the battery 13°, through the conductor 86 including the winding 87 of the line relay, cut-off relay contacts 15°—14°, line limbs 3—4, one strand of the “twin” winding 88 and cut-off relay contacts 89—90 to ground. The completion of this circuit energizes the line relay sufficiently to close the 20 circuit of the line lamp 25° at the contacts 29°—30°, thus causing the display of the line signal. Upon the insertion of the plug, 25 either in answering or making a call, current is supplied from the battery 49, over the sleeve side of the link-circuit, through the winding of the cut-off relay 16°, the connected strand of the “twin” winding 88 and the cut-off relay contacts 89—90 to ground. The closing of this circuit actuates the cut-off relay 16°, thereby breaking the grounded 30 connection to the center of the “twin” winding, disconnecting the battery 13° from the line, and depriving the line relay winding 87 of current. The removal of the ground connection to the “twin” winding permits the current to flow through both conductors of said winding and back over the tip strand of 35 the link-circuit to the grounded side of the battery 49. Thus, it will be seen that the “twin” winding 88 of the line relay 21°, and the winding of the cut-off relay 16°, are included in bridge of the telephone line limbs 40 and the resulting magnetic effect of one conductor of the “twin” winding neutralizes that of the other so that the relay contacts 29° and 30° are free to separate and break the circuit of the line lamp 25°. 45

In each of the forms illustrated in Figs. 2, 3 and 4, as well as in that illustrated in Fig. 1, the connection of the link-circuit to the line immediately operates to connect the relay windings in bridge of the telephone line; and 50 as soon as they are so connected, the associated supervisory signal will be displayed or effaced, according to whether the bridge at the substation is open or closed. In each of the line circuit arrangements illustrated in 55 Figs. 2, 3 and 4, the potential of the testing

contact of the jack is raised above its normal ground potential only after the connecting plug of a line circuit has been inserted, and not also in response to the removal of the receiver from its switch-hook at the substation, as is the case in the arrangement illustrated in Fig. 1. The testing operation on the part of the operator, however, is the same. 70

In the diagrams, the various ground connections should be understood as representing connections to ground or the usual common return of a central office; and in each instance, the various batteries, instead of being separate and distinct as shown, may be 75 one and the same. It is also obvious that other alterations and modifications may be made in the matter disclosed without departing from the spirit and scope of my invention. I, therefore, do not wish to be 80 limited to the specific matter illustrated, but aim to cover, by the terms of the appended claims, all such alterations and modifications. 85

In the accompanying claims I have used the term “cut-off” in a broad sense to define 90 that relay which, when operated, removes the control of the line signal from the subscriber.

What I claim as new and desire to secure by Letters Patent of the United States is:— 95

1. A telephone system comprising a telephone line extending from a substation to a central office, a line signal associated therewith, electromagnetically actuated means for normally controlling the display of said 100 signal, electromagnetically actuated means for destroying said control, one of said means having its energizing winding normally disconnected from said line, a link-circuit for making connection to said line, means for 105 holding conversation over said line and link-circuit, a source of current, and means operative upon the connection of said link-circuit to said line to connect energizing windings of both of said electromagnetically actuated 110 means in series bridge of said telephone line and in series with said source of current.

2. A telephone system comprising a telephone line extending from a substation to a central office, a line signal associated therewith, electromagnetically actuated means for normally controlling the display of said 115 signal, electromagnetically actuated means for destroying said control, a link-circuit for making connection to said line, means for holding conversation over said line and link-circuit, a supervisory signal associated with said link-circuit, and means operative upon the connection of said link-circuit to said line to complete a control circuit for said supervisory signal through energizing windings of both of said electromagnetically actuated 120 means in series bridge of said telephone line.

3. A telephone system comprising a telephone line extending from a substation to a 125

central office, a line signal associated therewith, a line relay for normally controlling the display of said signal, a cut-off relay having its energizing winding normally disconnected from said line and operative to destroy said control, a link-circuit for making connection to said line, means for holding conversation over said line and link-circuit, a source of current, and means operative upon the connection of said link-circuit to said line to connect energizing windings of said cut-off and line relays in series bridge of said telephone line and in series with said source of current.

4. A telephone system comprising a telephone line extending from a substation to a central office, a line signal associated therewith, a line relay for normally controlling the display of said signal, a cut-off relay for destroying said control, a link-circuit for making connection to said line, means for holding conversation over said line and link-circuit, a supervisory signal associated with said link-circuit, and means operative upon the connection of said link-circuit to said line to complete a control circuit for said supervisory signal through energizing windings of said cut-off and line relays in series bridge of said telephone line.

5. A telephone system comprising a telephone line extending from a substation to a central office, a line signal associated therewith, a line relay for normally controlling the display of said signal, a cut-off relay having its energizing winding normally disconnected from said line and operative to destroy said control, a link-circuit for making connection to said line, means for holding conversation over said line and link-circuit, means operative upon the connection of said link-circuit to said line to complete a circuit over portions of the connected line limbs and through energizing windings of said cut-off and line relays, means under the control of the subscriber for closing a path in shunt to said energizing windings, and means associated with said link-circuit for displaying a signal in response to the closing of said first-mentioned circuit and effacing said signal in response to the additional closing of said shunt path.

6. A telephone system comprising a telephone line extending from a substation to a central office, a line signal associated therewith, a line relay for normally controlling the display of said signal, a cut-off relay for destroying said control, a link-circuit for making connection to said line, means for holding conversation over said line and link-circuit, electrically actuated signal mechanism associated with said link-circuit and responsive to a given current flow through its winding to display its signal and to a different current flow to efface said signal, means operative upon the connection of said link-circuit to said line to cause the display of said signal by completing a circuit over portions of the con-

nected line limbs and through energizing windings of said cut-off and line relays in series, and means under the control of the subscriber for effacing said signal by varying the current through the winding of its mechanism.

7. A telephone system comprising a telephone line extending from a substation to a central office, a line signal associated therewith, a line relay for normally controlling the display of said signal, a cut-off relay for destroying said control, a link-circuit for making connection to said line, means for holding conversation over said line and link-circuit, electrically actuated signal mechanism associated with said link-circuit and responsive to a given current flow through its winding to display its signal and to a greater current flow to efface said signal, means operative upon the connection of said link-circuit to said line to cause the display of said signal by completing a circuit over portions of the connected line limbs and through energizing windings of said cut-off and line relays, and means under the control of the subscriber for effacing said signal by increasing the current in the winding of its mechanism.

8. A telephone system comprising a telephone line extending from a substation to a central office, a line signal associated therewith, a line relay for normally controlling the display of said signal having two energizing windings, a cut-off relay for destroying said control, means under the control of the subscriber for normally closing a circuit through both windings of said line relay to actuate it to cause the display of said signal, and means under the control of the operator for interrupting said subscriber's circuit and connecting one winding of said line relay and an energizing winding of said cut-off relay in bridge of said telephone line.

9. A telephone system comprising a telephone line extending from a substation to a central office, a line signal associated therewith, a line relay for normally controlling the display of said signal having two energizing windings, a cut-off relay for destroying said control, means normally under the control of the operator for closing a circuit at first through both windings of said line relay, and electromagnetically actuated means for subsequently connecting one winding of said relay and an energizing winding of said cut-off relay in bridge of said telephone line.

10. A telephone system comprising a telephone line extending from a substation to a central office, a line signal associated therewith, a line relay for normally controlling the display of said signal, a cut-off relay for destroying said control, a link-circuit for making connection to said line, means for holding conversation over said line and link-circuit, means operated upon the connection of said link-circuit to said line both to complete an

energizing circuit for said line relay and to close a portion of an energizing circuit for said cut-off relay, and means actuated by said line relay to complete the said cut-off relay circuit.

11. A telephone system comprising a telephone line extending from a substation to a central office, a line signal associated therewith, a line relay for normally controlling the display of said signal, a cut-off relay for destroying said control, a link-circuit for making connection to said line, means for holding conversation over said line and link-circuit, means operated upon the connection of said link-circuit to said line both to complete an energizing circuit for said line relay and to close a portion of an energizing circuit for said cut-off relay, means actuated by said line relay for completing said cut-off relay circuit, and means normally under the control of the subscriber for actuating said line relay.

12. A telephone system comprising a telephone line extending from a substation to a central office, a line signal associated therewith, a line relay for normally controlling the display of said signal, a cut-off relay for destroying said control, a link-circuit for making connection to said line, means for holding conversation over said line and link-circuit, means operated upon the connection of said link-circuit to said line both to complete an energizing circuit for the line relay including a portion of one connected line limb and to close a portion of an energizing circuit for said cut-off relay including a portion of the other connected line limb, and means actuated by said line relay for completing said cut-off relay circuit.

13. A telephone system comprising a telephone line extending from a substation to a central office, a line signal associated therewith, a line relay for normally controlling the display of said signal, a cut-off relay for destroying said control, a link-circuit for making connection to said line, means for holding conversation over said line and link-circuit, means operated upon the connection of said link-circuit to said line both to complete an energizing circuit for the line relay including a portion of one connected line limb and to close a portion of an energizing circuit for said cut-off relay including a portion of the other connected line limb, means actuated by said line relay for completing said cut-off relay circuit, and means normally under the control of the subscriber for actuating said line relay.

14. A telephone system comprising a telephone line extending from a substation to a central office, a line signal associated therewith, a line relay for normally controlling the display of said signal, a cut-off relay for destroying said control, a link-circuit for

making connection to said line, means for holding conversation over said line and link-circuit, means operative upon the connection of said link-circuit to said line both to complete an energizing circuit for the line relay including a portion of one connected line limb and to close a portion of an energizing circuit for said cut-off relay including a portion of the other connected line limb, means actuated by said line relay to complete said cut-off relay circuit, means under the control of the subscriber for completing a path in shunt to a portion of said completed cut-off relay circuit, and means associated with said link-circuit for displaying a signal in response to the completion of said cut-off relay circuit and for effacing said signal in response to the additional closing of said shunt path.

15. A telephone system comprising a telephone line extending from a substation to a central office, a line signal associated therewith, a line relay for normally controlling the display of said signal, a cut-off relay for destroying said control, a link-circuit for making connection to said line, means for holding conversation over said line and link-circuit, means operative upon the connection of said link-circuit to said line both to complete an energizing circuit for the line relay including a portion of one connected line limb and to close a portion of an energizing circuit for said cut-off relay including a portion of the other connected line limb, means actuated by said line relay to complete said cut-off relay circuit, means under the control of the subscriber operative normally to close an energizing circuit for said line relay and operative, when connection is established between said link-circuit and line, to close a path in shunt to a portion of the completed cut-off relay circuit, and means associated with said link-circuit for displaying a signal in response to the completion of said cut-off relay circuit and for effacing said signal in response to the additional closing of said shunt path.

16. A telephone system comprising a telephone line extending from a substation to a central office, a line signal associated therewith, a line relay for normally controlling the display of said signal, a cut-off relay for destroying said control, a link-circuit for making connection to said line, means for holding conversation over said line and link-circuit, electrically actuated signal mechanism associated with said link-circuit and responsive to a given current flow through its winding to display its signal and to a different current flow to efface said signal, means operative upon the connection of said link-circuit to said line both to complete an energizing circuit for the line relay including a portion of one connected line limb and to close a portion of an energizing

circuit for said cut-off relay and for said electrically actuated signal mechanism including a portion of the other connected line limb, means actuated by said line relay to 5 complete said cut-off relay circuit to actuate said cut-off relay and to display said link-circuit signal, and means under the control of the subscriber for effacing said link-circuit signal by varying the current through 10 the winding of its mechanism.

17. A telephone system comprising a telephone line extending from a substation to a central office, a line signal associated therewith, a line relay for normally controlling the display of said signal, a cut-off relay for destroying said control, a link-circuit for making connection to said line, means for holding conversation over said line and link-circuit, electrically actuated 15 signal mechanism associated with said link-circuit and responsive to a given current flow through its winding to display its signal and to a greater current flow to efface said signal, means operative upon the connection 20 of said link-circuit to said line both to complete an energizing circuit for the line relay including a portion of one connected line limb and to close a portion of an energizing circuit for said cut-off relay and for said 25 electrically actuated signal mechanism including a portion of the other connected line limb, means actuated by said line relay to complete said cut-off relay circuit to actuate 30 said cut-off relay and to display said link-circuit signal, and means under the control of the subscriber for effacing said link-circuit signal by increasing the current through 35 the winding of its mechanism.

18. A telephone system comprising a telephone line extending from a substation to a central office, a line signal associated therewith, a line relay for normally controlling the display of said signal, a cut-off relay for destroying said control, a link-circuit for making connection to said line, means for holding conversation over said line and link-circuit, electrically actuated 40 signal mechanism associated with said link-circuit and responsive to a given current flow through its winding to display its signal and to a different current flow to efface said signal, means operative upon the connection of said link-circuit to said line both to complete an energizing circuit for the line relay 45 including a portion of one connected line limb and to close a portion of an energizing circuit for said cut-off relay and for said electrically actuated signal mechanism including a portion of the other connected line 50 limb, means actuated by said line relay to complete said circuit to actuate said cut-off relay and to display said link-circuit signal, and means under the control of the subscriber operative normally to close an en-

ergizing circuit for said line relay and operative, when connection is established between said link-circuit and line, to efface said link-circuit signal by varying the current through the winding of its mechanism. 65

19. A telephone system comprising a telephone line extending from a substation to a central office, a line signal associated therewith, a line relay for normally controlling the display of said signal, a cut-off relay for destroying said control, a link-circuit for making connection to said line, means for holding conversation over said line and link-circuit, electrically actuated signal mechanism associated with said link-circuit and responsive to a given current 70 flow through its winding to display its signal and to a greater current flow to efface said signal, means operative upon the connection of said link-circuit to said line both to complete an energizing circuit for the line relay 75 including a portion of one connected line limb and to close a portion of an energizing circuit for said cut-off relay and for said electrically actuated signal mechanism including a portion of the other connected line 80 limb, means actuated by said line relay to complete said cut-off relay circuit to actuate said cut-off relay and to display said link-circuit signal, and means under the control of the subscriber operative normally to close an energizing circuit for said line relay and operative, when connection is established between said link-circuit and line, to efface said link-circuit signal by increasing the current 85 through the winding of its mechanism. 90

20. A telephone system comprising a telephone line extending from a substation to a central office, a line signal associated therewith, a line relay for normally controlling the display of said signal having two energizing 105 windings, a cut-off relay for destroying said control, means under the control of the subscriber for normally closing a circuit through both windings of said line relay to actuate it to cause the display of said signal, means under the control of the operator for closing a circuit through both windings of said line relay and electromagnetically actuated means for subsequently closing a circuit through an energizing winding of said cut-off relay. 110

21. A telephone system comprising a telephone line extending from a substation to a central office, a line signal associated therewith, a line relay for normally controlling the display of said signal having two energizing 120 windings, a cut-off relay for destroying said control, means under the control of the subscriber for normally closing a circuit through both windings of said line relay to actuate it to cause the display of said signal, means under the control of the operator for closing a circuit through both windings of said line relay and electromagnetically actuated means 125

for subsequently closing a circuit through one of said windings only and an energizing winding of said cut-off relay.

22. A telephone system comprising a telephone line extending from a substation to a central office, a line signal associated therewith, a line relay for normally controlling the display of said signal having two energizing windings of different numbers of turns, a cut-off relay for destroying the normal line relay control of said signal, means under the control of the subscriber for normally closing a circuit through both windings of said line relay to actuate it to cause the display of said signal, and means under the control of the operator for closing a circuit at first through both windings of said line relay, and subsequently through the winding of a lesser number of turns of said line relay and an energizing winding of said cut-off relay.

23. A telephone system comprising a telephone line extending from a substation to a central office, a line signal associated therewith, a line relay for normally controlling the display of said signal having two energizing windings, a cut-off relay for destroying said control operative only when said line relay is in its actuated position, means under the control of the subscriber for normally closing a circuit through both windings of said line relay to actuate it to cause the display of said signal, and means under the control of the operator for interrupting the subscriber's circuit through both windings of said line relay and closing a circuit through one of said windings to maintain said line relay in its actuated position.

24. A telephone system comprising a telephone line extending from a substation to a central office, a line signal associated therewith, a line relay for normally controlling the display of said signal having two energizing windings, a cut-off relay for destroying said control operative only when said line relay is in its actuated position, means under the control of the subscriber for normally closing a circuit through both windings of said line relay to actuate it to cause the display of said signal, and means under the control of the operator for interrupting the subscriber's circuit through both windings of said line relay and closing a circuit through one of said windings and through an energizing winding of said cut-off relay to maintain the line relay in its actuated position and to actuate said cut-off relay.

25. A telephone system comprising a telephone line extending from a substation to a central office, a line signal associated therewith, a line relay for normally controlling the display of said signal having two energizing windings, a cut-off relay for destroying said control operative only when said line relay is in its actuated position, and means

under the control of the operator for normally closing a circuit through both windings of said line relay to actuate it and subsequently closing a circuit through one only of said windings to maintain said line relay in its actuated position.

26. A telephone system comprising a telephone line extending from a substation to a central office, a line signal associated therewith, a line relay for normally controlling the display of said signal having two energizing windings, a cut-off relay for destroying said control operative only when said line relay is in its actuated position, means under the control of the operator for normally closing a circuit through both windings of said line relay to actuate it, and electromagnetically actuated means for subsequently closing a circuit through one of said windings and through an energizing winding of said cut-off relay to maintain said line relay in its actuated position and to actuate said cut-off relay.

27. A telephone system comprising a telephone line extending from a substation to a central office, a line signal associated therewith, a line relay for normally controlling the display of said signal having two energizing windings of different numbers of turns, means under the control of the subscriber for closing a circuit through said windings in opposition to actuate said relay to cause the display of said signal, and means under the control of the operator for cutting said line relay winding of a greater number of turns out of circuit and reversing the direction of current flow in said winding of a lesser number of turns, thereby to maintain said relay in its actuated position.

28. A telephone system comprising a telephone line extending from a substation to a central office, a line signal associated therewith, a line relay for normally controlling the display of said signal having two energizing windings of different numbers of turns, a cut-off relay for destroying said control operative only when said line relay is in its actuated position, means under the control of the subscriber for closing a circuit through the windings of said line relay in opposition to actuate said relay to cause the display of said signal, and means under the control of the operator for cutting said line relay winding of a greater number of turns out of circuit and reversing the direction of current flow in said winding of a lesser number of turns, thereby to maintain said relay in its actuated position.

29. A telephone system comprising a telephone line extending from a substation to a central office, a line signal associated therewith, a line relay for normally controlling the display of said signal having two energizing windings of different numbers of turns, a cut-off relay for destroying said control operative

- only when said line relay is in its actuated position, means under the control of the subscriber for closing a circuit through the windings of said line relay in opposition to actuate 5 said relay to cause the display of said signal, and means under the control of the operator for cutting said line relay winding of a greater number of turns out of circuit and reversing the direction of current flow in said winding 10 of a lesser number of turns by including it in circuit with an energizing winding of said cut-off relay, thereby to maintain said line relay in its actuated position and to actuate said cut-off relay.
- 15 30. A telephone system comprising a telephone line extending in two limbs from a substation to a central office, a connection terminal for said line having a testing contact, a battery, means under the control of the subscriber for establishing a definite busy connection between said testing contact and one pole of said battery, means for enabling the operator to determine the idle or busy condition of the line by touching the tip of the 20 connecting plug to said testing contact, and means responsive to the connection of said line and link-circuit to interrupt said definite busy connection between said testing contact and battery.
- 25 31. A telephone system comprising a telephone line extending in two limbs from a substation to a central office, a connection terminal for said line having a testing contact, a battery, a two-strand link-circuit and connecting plug for establishing connection with said line, a relay operative, when energized, to establish a definite busy connection between said testing contact and one pole of said battery, means under the control of the 30 subscriber for energizing said relay, means for enabling the operator to determine the idle or busy condition of the line by touching the tip of the connecting plug to said testing contact, and means responsive to the connection of said line and link-circuit to interrupt said definite busy connection between said testing contact and battery.
- 35 32. A telephone system comprising a telephone line extending in two limbs from a substation to a central office, a connection terminal therefor, having a testing contact, a battery, a two-strand link-circuit and two-contact connecting plug for establishing connection with said line, a signal associated 40 with said line, a line relay for normally controlling the display of said signal, a cut-off relay for destroying said control, means actuated by the energization of said line relay to establish a definite busy connection 45 between said testing contact and one pole of said battery, means under the control of the subscriber for energizing said line relay, means for enabling the operator to deter-

mine the idle or busy condition of the line by touching the tip of the connecting plug to 65 said testing contact, and means responsive to the connection of said line and link-circuit to interrupt said definite busy connection between said testing contact and battery.

33. A telephone system comprising a telephone line extending from a substation to a central office, connection terminals therefor, a link-circuit and connecting plug for establishing connection with said line, a signal associated with said line, a line relay for 70 normally controlling the display of said signal, a cut-off relay for destroying said control, means actuated by the energization of said line relay to modify the connections of the testing contacts of said terminals to 75 vary their potential and to connect the energizing windings of said line and cut-off relays in bridge of said connection terminals, means under the control of the subscriber for energizing said line relay, and means for enabling the operator to determine the idle or busy condition of the line by touching the tip of the connecting plug to one of said contacts.

34. A telephone system comprising a telephone line extending from a substation to a central office, a line signal associated therewith, a line relay for normally controlling the display of said signal having two energizing windings, a cut-off relay for destroying said control, means normally under the control 90 of the operator for closing a circuit through both windings of said line relay and electro-magnetically actuated means for subsequently connecting one winding of said line relay and an energizing winding of said cut-off relay in series bridge of said telephone line.

35. A telephone system comprising a telephone line extending from a substation to a central office, a line signal associated therewith, a line relay for normally controlling the display of said signal having two energizing windings, a cut-off relay for destroying said control, means under the control of the subscriber for normally closing a circuit through 95 both windings of said line relay to actuate it to cause the display of said signal, and means under the control of the operator for closing a circuit at first through both windings of said line relay and subsequently through one 100 of said windings only and an energizing winding of said cut-off relay.

36. A telephone system comprising a telephone line extending from a substation to a central office, a line signal associated therewith, a line relay for normally controlling the display of said signal having two energizing windings, a cut-off relay for destroying said control operative only when said line relay is in its actuated position, means 120 under the control of the operator for nor-

mally closing a circuit at first through both windings of said line relay to actuate it and subsequently through one of said windings only and an energizing winding of said cut-off relay to maintain said line relay in its actuated position and to actuate said cut-off relay.

In witness whereof, I hereunto subscribe my name this 8th day of February, A. D., 1906.

HARRY G. WEBSTER.
